PROPELLENT CARTRIDGE FOR MORTAR SHELLS

Melvin J. Standal, Minneapolis, Minn., assignor to Federal Cartridge Corporation, Minneapolis, Minn., a corporation of Minnesota

Application August 22, 1944, Serial No. 550,527

4 Claims. (Cl. 102—39)

1

This invention relates to mortar shells used as propelling and ignition devices for mortar bombs. In use a mortar shell is inserted into a barrel-like protuberance on the end of the mortar bomb and the entire bomb is dropped into the mortar barrel down which it slides until it hits a firing pin located centrally in the bottom of the mortar barrel. The firing pin engages the percussion cap of the mortar shell and the ensuing explosion propels the mortar bomb from the barrel of the mortar. In some instances the entire propelling force is provided by the mortar shell while in other instances the mortar shell serves merely as the igniter for rings of mortar propellant powders that are fastened on the back end of the mortar bomb.

During the early part of the war between the United States and the Japanese during the fighting in the South Pacific Islands, it was found that mortar shells frequently failed to explode and in many instances became unusable. The cause of failure was traced to the high temperatures and high humidity conditions existing in the South Pacific Islands where not infrequently the humidity may be 80-90% and even higher, and the temperature well over 100° F. In other areas of conflict the mortar must be capable of unvarying performance even under extremely cold conditions and accordingly ignition therefore including the mortar shell propellant and/or ignition device must be capable of unvarying response not only under extremely cold conditions, but also under extremely warm and moist conditions, even after months of storage.

It is an object of the present invention to provide an improved mortar shell of rugged and reliable construction capable of unvarying and uniform performance under extremely wide variations of temperature from well below 0° F. to well above 100° F. and under conditions of extreme humidity variation. It is a more specific object of the invention to provide a mortar shell of water and moisture impervious construction capable of withstanding storage for months at temperatures well over 100° F. and under humidity conditions approaching saturation, and at the same time capable of withstanding exceedingly cold, dry climatic conditions such as temperatures of 40° F. below zero. It is a specific object of the invention to provide an improved mortar shell of water-proof and moisture impervious construction capable of maintaining its gauge throughout its useful life under such climatic conditions.

Other and further objects of the invention are

2

those inherent in the apparatus herein illustrated, described and claimed.

The invention is illustrated with reference to the drawings in which

5 Figure 1 is an elevational view partly in section showing the mortar shell of the present invention before being exploded;

10 Figure 2 is an elevational view partly in section of the mortar shell of the present invention after being exploded;

15 Figures 3 and 4 are fragmentary sectional views illustrating modified forms of the invention.

Throughout the drawings corresponding numerals refer to the same parts.

20 Referring to the drawings the mortar shell comprises a paper tube 10 having one end closed by means of the usual thin metal shotgun shell cup generally designated 11 consisting of side walls 12 which are inside chamfered at 13 and a base

25 14 which is centrally apertured to receive the primer 15. Within the paper tube 10 there is a paper liner 16 and base wad or wads 17. The paper tube 11, as usually constructed, is paraffin impregnated, the liner 16 being either unimpregnated or impregnated, as desired. The liner 16 is preferably terminated at the level 18 and serves as a positioning device for the paper cardboard wad 20.

30 Over the cardboard wad 20 there is positioned a lead wad 22 and over this another cardboard wad 23. The end of the paper tube 10 is crimped inwardly as illustrated at 25 so as to retain the wads tightly in place. This much of the construction may be regarded as prior practice.

35 It was found that shells so constructed without the covering cap generally designated 30, herein-after described, failed when subjected to extreme climatic conditions of temperature and humidity such as encountered in the South Pacific and numerous tests were run utilizing impregnated coatings of all sorts in an attempt to obtain satisfactory water and moisture resistance. Tests were made without avail.

40 In accordance with the present invention such satisfactory water and moisture resistance is obtained by enclosing the entire end of the mortar shell by means of a cup generally designated 30 which is preferably made of the same material and upon the same machines used in fabricating the cup 11. Cup 30 may conveniently be made upon the same machines as

45 used in fabricating cup 11. Thus, during manufacture of cup 11, it is drawn to the shape of cup 30, and then further pressed so as partially to form flange 19. The cup with the partially formed flange is placed upon tube 10 and pressed

to contract it upon tube 10 and finish the flange 19 to the shape shown in Figure 1. The beadings 21 are also formed to serve as an additional grip on the tube. Hence, cups 30 may conveniently be diverted before any ejector flange is formed, there being at this stage a smoothly rounded shoulder at 31. The cup 30 is then pressed onto the crimp closed end of the shell tube 10 and in the pressing operation is drawn down to a somewhat smaller diameter so as to embed the side wall 32 of the cup into the cardboard material making up the tube 10. The cup 30 is preferably slightly chamfered inside at the mouth 33 before being assembled onto the shell tube 10 and is beaded in at 34 directly opposite the lead washer 22, thus compressing the cardboard material of tube 10 between the beading 34 and the lead washer. In this way there is a very firm and a very water-proof attachment of the cup 30 to the end of the shell.

For best water and moisture-proofing practice it is desirable to coat the shell 10 with lacquer, varnish, shellac, drying oils, asphalt varnishes, or other water-proofing materials, prior to the assembly of the cup 30 thereon. Inasmuch as the shell tube 10 is usually prepared of paraffin impregnated paper, the crimp closed shell just before assembly of the cup 30 thereon, may be surface dewaxed in accordance with the method and apparatus set forth in the copending application of William N. King entitled Method of finishing containers impregnated with wax, Ser. No. 550,667, now Patent No. 2,413,144, filed concurrently herewith. In accordance with the method and apparatus of said application the wax is removed from the surface of the crimp closed cartridge and is in a suitable condition for application of water-proofing material which may conveniently be accomplished by dipping the shell into a lacquer bath to a depth so as to cover the entire exposed cardboard tube 10, the end wad 23 and a portion at least of the cup 11. In the dipping operation of course the shell is inverted from the position shown in Figure 1. The lacquer is then dried, preferably by an oven or radiant heat drying technique, and the cup 30 is then assembled on the shell as previously described. A second coat of lacquer is then applied over the cup 30, the exposed side wall of the tube 10 and a portion of the cup 11. In order to complete the water-proofing operation the head end 14 of the cup 11 is given a dob of water-proofing varnish over the primer cup, thereby sealing the joint between the primer cup 15 and the head portion 14 of the cup 11. If desired, one or two coats of lacquer may be applied after the cup 30 is in place thereon, after dewaxing the exposed surface of tube 10.

Mortar shells so fabricated are capable of functioning satisfactorily after 48 hours of immersion at a depth of two feet in a water solution containing 3% sodium chloride. The shells likewise withstand three months storage at 85% relative humidity and at a temperature of 115° F. The shells withstand storage indefinitely at 65° F. There is an inappreciable increase in gauge (swelling) after such immersion test in a water solution containing 3% sodium chloride at a depth of two feet, and when fired within 30 minutes after the immersion test, perform in a uniformly satisfactory manner and produce an average pressure in a standard shot shell pressure gun of not more than 10% variation from the average as established by shells not so submerged.

Figure 2 illustrates the shotgun shell as it appears when fired in a standard mortar. It will be noted that the cup 30 remains in place, the gases from the explosive charge being discharged outwardly through a series of perforations 38, the number and position of which are determined by apertures in the barrel of the mortar bomb in which the shell is used. It may be stated parenthetically that the propellant used for mortar bombs is made in the shape of rings that are mounted on the barrel in which the ignition cartridge is positioned and the barrel is apertured along its side wall so that when the ignition cartridge explodes the hot gases therefrom will be discharged outwardly through the apertures directly into the ring of propellant powder in the outside of the barrel which are then ignited and explode, propelling the bomb from the mortar.

It will be appreciated, of course, that any standard form of crimp such as the unfolded crimp illustrated in Figure 3 may be utilized with the water-proofing and protecting cup 30 of the present invention. Thus, as shown in Figure 3 the tube side wall 40 is unfolded in gores, to form an end crimp 41 over the paper wad 23, lead wad 22 and paper wad 20. The entire end of the cartridge is then enclosed by means of the cup generally designated 30 as in Figure 1 and the cup beaded as illustrated at 34 so as to compress the side wall of the tube 40 against the lead wad 22. This construction eliminates all or most of the dead air space 36 of the construction shown in Figure 1.

Likewise, as illustrated in Figure 4, there may be utilized a construction wherein the paper tube 50 of the shell is not crimped at all, being merely plugged by the series of wads, including the paper wad 20, lead wad 22 and the paper wad 23. Over the thus closed end of the shell tube 50 there is then placed the end closure cup generally designated 30 of the type illustrated in Figure 1, which is inwardly beaded as illustrated at 34 so as to compress the tube 50 between the beading 34 and the lead wad 22. In this construction illustrated in Figure 4 the waterproofing depends largely upon the cup 30 and is satisfactory in many instances.

In any of the foregoing constructions by utilizing only one cardboard end wad 23 instead of the paper and lead wads 20, 22 and 23, and by using an exceedingly thin metal or plastic cup 30, or a cup 30 wherein the part 37 is exceedingly thin, the present construction may be applied satisfactorily to the closure of standard shotgun shells where the propellant gases and load will discharge from the end of the tube rather than through the tube side wall as shown in Figure 2. When so utilized the cup 30 simply fractures around the corner 31, the crimp, if used, unfolds and the entire propellant gases, wadding and load are discharged in the usual manner.

As many apparently widely different embodiments of this invention may be made without departing from the spirit and scope thereof, it is to be understood that I do not limit myself to the specific embodiments herein except as defined by the appended claims.

What I claim is:

1. An explosive ammunition comprising a cylindrical paper tube which is adapted to be fractured when the ammunition is exploded, said tube having an outwardly flanged base closure cup pressed onto one end of the tube, said base closure cup being provided with a percussion cap, an explosive charge within the tube, an end wad

including a stiff disc closing the end of the tube opposite the base closure cup, said end wad being held in place by inwardly crimping of the tube side wall, and a cylindrical closed end waterproofing cup pressed onto the crimped end of the tube, the outer diameter of said cup being substantially the same as the outer diameter of the tube, said cylindrical closed end cup being attached solely by being pressed onto the tube and crimped inwardly circumferentially at a position so as to compress the tube paper against the stiff end wad disc thereby to maintain said cup immovably attached to the tube at explosive pressures sufficient to rupture the wall of the paper tube.

2. An explosive ammunition comprising a cylindrical paper tube having an outwardly flanged metallic base closure cup pressed onto one end of the tube, said base closure cup being provided with a percussion cap, an explosive charge within the tube, an end wad including a metallic disc closing the end of the tube, said end wad being held in place by a crimp formed in the end of the paper tube side wall, and a thin metal, closed end cylindrical walled closure cup attached to the tube solely by being pressed and squeezed onto the end of the tube that is closed by said end wad and thereby attached sufficiently to resist displacement when the explosive pressure increases sufficiently to rupture the side walls of the paper tube.

3. An explosive ammunition comprising a cylindrical paper tube having an outwardly flanged metallic base closure cup pressed onto one end of the tube, said base closure cup being provided with a percussion cap, an explosive charge within the tube, an end wad including a metallic disc closing the end of the tube and a thin metal, closed end cylindrical walled closure cup attached to the tube solely by being pressed onto the end

of the tube that is closed by said end wad and drawn down in circumference, said closure cup being beaded inwardly at a level substantially coinciding with the position of the metallic disc.

4. An explosive ammunition comprising a cylindrical paper tube having an outwardly flanged metallic base closure cup pressed onto one end of the tube, said base closure cup being provided with a percussion cap, an explosive charge within the tube, an end wad including a metallic disc closing the end of the tube and a thin metal, closed end cylindrical walled closure cup attached to the tube solely by being pressed and drawn down in circumference onto the end of the tube that is closed by said end wad, said closure cup being beaded inwardly at a level substantially coinciding with the position of the metallic disc, said ammunition being lacquer coated.
